UNITED STATES PATENT OFFICE.

MARTIN T. ASH, OF SHIRLEY, WEST VIRGINIA, ASSIGNOR OF ONE-HALF TO TILMAN E. ASH, OF ASHLEY, DODDRIDGE COUNTY, WEST VIRGINIA.

VALVE.

1,195,958.

Specification of Letters Patent. Patented Aug. 29, 1916.

Application filed February 20, 1915. Serial No. 9,620.

To all whom it may concern:

Be it known that I, MARTIN T. ASH, a citizen of the United States, residing at Shirley, in the county of Tyler and State of West Virginia, have invented certain new and useful Improvements in Valves; and I do hereby declare the following to be a full, clear, and exact description of the invention, such as will enable others skilled in the art to which it appertains to make and use the same.

This invention relates to valves, and the primary object of the invention is to provide a valve construction, by means of which the water inlet into a pipe may be positioned interiorly of a tank, for preventing freezing of the inlet during cold weather.

Another object of this invention is to provide a valve including a rotatable valve stem having suitable valve mechanism carried upon one end thereof, which controls the inlet of liquid into a pipe, which extends into the liquid retaining receptacle, a considerable distance beyond the inner surface 25 of the walls of the receptacle.

With the foregoing and other objects in view this invention consists in such novel features of construction, combination and arrangement of parts as will be hereinafter 30 more fully described, illustrated in the accompanying drawings and claimed.

In describing the invention in detail reference will be had to the accompanying drawings wherein like characters designate 35 like or corresponding parts throughout the several views, and in which:—

Figure 1 is a side elevation of the improved valve, showing the same applied to a fragment of a liquid retaining receptacle, 40 and Fig. 2 is a horizontal section through the improved valve.

Referring more particularly to the drawings, 1 designates a T-pipe joint, which has one end detachably connected to a liquid retaining receptacle 2. A pipe 3 is connected to the central opening in the T-joint 1, and a sleeve 4 to the other end of the T-joint, and in alinement with the end which is connected to the receptacle 2. The sleeve 4 has 45 an enlarged head 5 formed thereupon, which is detachably inserted in the end 6 of the T-joint 1 and extends outwardly therefrom. The sleeve 4 has a valve stem 7 rotatably mounted therein, which valve stem is provided with a plurality of external screw

threads 8 formed on a section of its length, which mesh with internal screw threads 9 formed on a section of the length of the bore of the sleeve 4, for permitting of the longitudinal seating of the valve stem 7 to 60 the sleeve 4 upon rotation of the former.

The ordinary type of stuffing box 10 is mounted in the outer end of the sleeve 4, and the valve stem 7 has a hand wheel 11 or any other suitable mechanism for rotating the same, mounted upon its outer end.

The end 12 of the T-joint 1, which is connected to the casing or liquid retaining receptacle 2, has a length 13 of pipe secured thereto which extends inwardly into the 70 interior of the receptacle 2. The length 13 of pipe extends into the receptacle 2 sufficient distance to position the open end of the same far enough inwardly from the inner walls of the receptacle 2, for preventing 75 any possibility of the freezing up of the end of the pipe except when the entire content of the receptacle is frozen.

The valve stem 7 has a collar 14 detachably mounted upon its outer end, to which 80 collar is connected a valve cone 15. The valve cone 15 is mounted upon the end of the valve stem 7 and it has a sleeve 15' projecting from its enlarged end, which sleeve 85 encompasses the collar 14, and is provided with external screw threads formed upon its outer surface. The valve cone 15 tapers inwardly from the sleeve 15' and it has its face or outer end of practically the same diameter as the bore of the length 13 of 90 pipe. A nut 16 is detachably mounted upon the sleeve 15' and it has its outer end closed. The inner edge of the nut 16 engages a metallic washer 17, which washer in turn 95 lies in flat abutment with or against a flexible valve washer 18. The flexible valve washer 18 engages the base of the valve cone 15 and is provided for forming a fluid-tight close for the open end of the pipe 13.

When the valve stem 7 is rotated in one 100 direction, it will move the washer 18 out of engagement with the end of the pipe 13, and also move the cone 15 outwardly, which will regulate the amount of liquid which flows into the pipe 13 and through the same, flowing through the T-joint 1 and the pipe 3. By moving the cone 15 outwardly within the pipe 13, the space between the outer surface of the cone and the inner wall or surface of the pipe 13 will be increased, by 110

means of which the quantity of liquid which flows into and through the pipe 13 may be regulated. By rotating the valve stem 7 in a reverse direction, the cone 15 5 will be moved into the pipe 13 and the disk 18 brought into engagement with the end of the pipe which will cut off the flow of liquid therein. By positioning the inlet end of the pipe 13 inwardly from the walls or 10 sides of the receptacle 2, the liability of the mouth of the pipe 13 and the valve cone carried thereby freezing is materially decreased.

In reducing the invention to practice, certain minor features of construction, combination, and arrangement of parts may 15 necessitate alteration, to which the patentee is entitled, provided such alterations are comprehended within the scope of what is 20 claimed.

What is claimed is:—

A valve comprising a T-joint having one end adapted to be connected to a receptacle; a closure detachably connected to one end of the T-joint; a valve stem rotatably car-

ried by said closure to extend through said T-joint; a length of pipe screw threadedly connected to said T-joint to extend into said liquid retaining receptacle; a collar removably secured to the inner end of said stem; 30 a valve cone provided at its enlarged end with a sleeve fitted over said collar; the sleeve being exteriorly screw threaded; said valve cone tapering inwardly from the sleeve, and a washer fitted over said sleeve 35 and one face engaging the face of the valve cone; a disk fitted over said sleeve, and engaging said washer; a nut screw-threadedly fitted on said sleeve for holding said disk and washer into engagement with the base 40 of the valve cone; the lower end of the sleeve forming a liquid tight joint at its point of engagement with the cone valve washer.

In testimony whereof I affix my signature 45 in presence of two witnesses.

MARTIN T. ASH.
